UNITED STATES PATENT OFFICE

171,279

SWIVEL JOINT

Donald Manning Jackson, Brea, Calif., assignor to
Chiksan Company, Brea, Calif., a corporation
of California

Application January 2, 1953, Serial No. 22,985

Term of patent 14 years

(Cl. D91—3)

To all whom it may concern:

Be it known that I, Donald Manning Jackson, a citizen of the United States, residing in the city of Brea, county of Orange, and State of California, have invented a new, original, and ornamental Design for a Swivel Joint, of which the following is a specification, reference being had to the accompanying drawings, forming a part thereof.

Fig. 1 is a perspective view of a swivel joint, embodying my new design showing the top, one side and one end. Fig. 2 is a perspective view similar to Fig. 1 and showing the top, the other end and other side of my new design. Fig. 3 is a side elevational view of my new design. Fig.

4 is an end elevation of my new design. Fig. 5 is a bottom plan view thereof.

I claim:

The ornamental design for a swivel joint, as shown.

DONALD MANNING JACKSON.
